LOCK

George W. Wardwell, Jr., Trumbull, Conn., assignor to Sargent & Company, New Haven, Conn., a corporation of Connecticut

Application May 9, 1946, Serial No. 668,401

8 Claims. (Cl. 292—169)

1

This invention relates to door locks, and more particularly to a lock mounted in a cylindrical case designed to be inserted in a bore in the edge of a door, and which case is adapted to pass through an opening in a cylindrical aligning tube which may be inserted in a bore through the face of the door.

In tubular locks, it is more or less customary to employ a bolt case which is inserted in a bore made through the edge of the door and to pass through this case a spindle connected to knobs at the inner and outer faces of the door, which spindle is designed to actuate the bolt-retracting mechanism. As the spindle is aligned by the cylindrical case in which the knobs are carried, it sometimes occurs that this knob case does not stand in the proper position with respect to the bolt mechanism case and, in that event, the spindle will tend to bind. This often is a result of the fact that the knob spindle is not accurately placed at right angles to the direction of reciprocation of the bolt, but may also be due to other errors in the mounting of parts.

Moreover, it is desirable that a firm and rigid connection be made between the two housings or casings, that is, between the housing which carries the bolt and bolt-actuating mechanism and the housing which carries the knobs, and it is also desirable that the lock be universal in character in that it may be capable of being mounted on a door of either hand and which opens in either direction without any alteration in the position of the parts. That is to say, the lock should be capable of being used with a door of either hand and bevel without removing any parts from the case and changing their position.

One object of the present invention is to provide a door lock of relatively simple construction which may be universally employed regardless of the direction in which the door opens and regardless of whether the door opens from the right- or left-hand side.

A still further object of the invention is to provide a door lock of relatively simple construction which may be readily installed through cylindrical openings or bores made through the door and into the edge of the door, and the parts of which will be so arranged that there will be no tendency for them to bind or fail to operate freely.

A still further object of the invention is to provide a door lock of the character described which shall be provided with novel means for dogging one of the knobs against rotation.

Still another object of the invention is to provide a lock of the character described which shall

2

be provided with novel means for guarding or dogging the latch bolt against being forced rearwardly or retracted by a tool inserted between the edge of the door and the door jamb.

To these and other ends the invention consists in the novel features and combinations of parts to be hereinafter described and claimed.

In the accompanying drawings:

Fig. 1 is a sectional view of a door lock embodying my new invention, the lock being shown in mounted position upon a door;

Fig. 2 is a partial sectional view on line 2—2 of Fig. 1;

Fig. 3 is a sectional view on line 3—3 of Fig. 1; Figs. 4 and 5 are views similar to Fig. 3, but showing the parts in different positions;

Fig. 6 is a partial sectional view on line 6—6 of Fig. 1;

Fig. 7 is a detail view of the latch bolt retractor; and

Fig. 8 is a detail view of the dogging plunger mounted on the inside knob.

To illustrate a preferred embodiment of my invention, I have shown a door lock comprising a case 10 of cylindrical shape, this case being adapted to contain the latch bolt and actuating mechanism therefor as will be hereinafter explained, and also being adapted, when inserted within the bore 10^a in the edge of the door, to pass through an opening 11 (Fig. 2) in the body portion 12 of a cylindrical aligning tube adapted to be inserted in a bore 13 bored through the face of the door.

A latch bolt is reciprocably mounted in the case 10, this bolt comprising a beveled head 14 and a stem 15, this stem passing loosely at its rear end through an opening 16 in a bolt retractor shown in Fig. 7. This retractor comprises a pair of members of substantially identical shape, each comprising a substantially semi-circular head, which heads together form a disk-like member 17, and a pair of flat stems 18 which project rearwardly from the portion 17 and which are secured together in pairs by spacing pins 19. The stem 15 is provided with a head 20 rearwardly of the part 17 of the retractor so that movement of the latter will carry the bolt therewith, although the bolt may move independently of the retractor, the stem 15 sliding through the opening 16.

In order to hold the retractor in extended position, a spring 21 acts between the disk 17 and a stop plate 22 within the lock case, the spring surrounding a post 23 which extends through an opening in the member 17. In order to urge the bolt to projected position, a second spring 24 is

disposed between the bolt head and the member 17. It will be seen, therefore, that when the bolt 14 is retracted by engagement with the strike plate of the door jamb it is not necessary to compress the relatively strong spring 21 in order to move the bolt head into the case. The stop plate 22 is held in place by a yoke 25 inserted into the rear end of the lock case, which yoke, as will be hereinafter explained, serves as a support for certain parts of the mechanism within the casting, this yoke being held in place by the screw 26.

Rotatably mounted in transverse openings in the yoke 25 are inner and outer rollback hubs 27 and 28, these hubs carrying rollbacks 29 and 30 and having aligned openings therein for the reception of the knob spindle, as will be herein-after explained. These rollbacks 29 and 30 are adapted to engage laterally turned lugs 31 and 32 carried by bridge members 33 which span the retractor stems 18, as shown more especially in Figs. 3 to 5 and 7, so that upon the turning of the rollbacks the retractor will be drawn rearwardly and the latch bolt retracted into the case. The member 33 is held in place by the laterally turned lugs 34 on the rear end of the stems 18. The rollback hubs are additionally held in place in the openings in the yoke 25 by the members 35 and 35^a secured in the rear part of the yoke 25 by the pin 36, which members 35 and 35^a also guide the retractor at the end of its travel.

The aligning tube which supports the knob and the spindle mechanism is also of cylindrical shape and comprises a main portion 12 and reduced end portions or sleeves 38 and 39, these sleeves being threaded exteriorly and provided with internal bores of the same size as that of the main portion 12, which latter bore is at right angles to the opening 11 which receives the case 10.

The outer knob is shown at 40 (Fig. 1), this knob having a shank 42 rotatably mounted within the sleeve 39 and retained therein by means of a key 43 which enters an annular slot 44 in the knob shank and is disposed in an opening 45 adjacent the outer edge of the central portion 12 of the aligning tube. This key may be held in place by a pin 46 and secures the knob to the aligning tube 12, while at the same time permits free rotation thereof. Mounted in this knob is a key-operated lock shown conventionally at 47, the use of which will be hereinafter explained.

The inner knob is shown at 48, and is likewise provided with a shank 49 rotatably mounted in the sleeve 38 and retained in place by a U-shaped spring member 50 embracing the sleeve and having its legs lying in the annular recess 51. Escutcheons or roses 52 are mounted at the inner and outer surfaces of the door, these roses being held in place by sleeves 53 threaded upon the sleeves 38 and 39, the roses covering the outer end portions of the aligning tube.

As shown more particularly in Figs. 1 and 2, a knob spindle 55 is provided which extends through the case of the lock mechanism and engages one of the rollback hubs to rotate the same upon the turning of the inner knob. This spindle is of generally cylindrical shape, but is provided with a squared portion 56 non-rotatably received within a correspondingly shaped opening in the knob shank 49, and is also provided with a squared portion 57 which lies within a similarly shaped opening in the inner rollback hub 27, this spindle being urged toward the knob 48 by the spring 58 which surrounds the spindle and acts against a washer 59 on one end of the spindle.

Adjacent its other end, the spindle is reduced

in size, as shown at 60, and upon this reduced end is rotatably mounted a sleeve 61 having a squared portion 62 disposed in a squared opening in the outer rollback hub 28 and a second squared portion 63 disposed within a similarly shaped opening 64 in the shank of the outer knob so that, when the outer knob is turned, the sleeve 61 will be rotated, and, if the parts are in the position shown in Fig. 1, will rotate the outer 10 rollback 30 and retract the latch. It may here be noted that at this side of the case 10 adjacent the outer rollback 30, there is provided a square opening 65 to receive the squared portion 62 of the sleeve 61. There is also provided at the other 15 side of case 10 a similarly placed square opening 65^a which will receive the squared portion 62 of the sleeve 61 if it is desired to turn the latch bolt over for a reverse bevel application.

The reduced end 60 of the spindle 55 extends 20 through the sleeve 61 and is connected with the key-operated lock 47 in the outer knob, so that the spindle 55 may be rotated by this lock when the sleeve 61 and outer knob are dogged against rotation. The connection between the reduced 25 end of the spindle and the lock is a lost motion connection and comprises a pin 101 secured to the key barrel 102, which pin is received in a transverse slot 103 in a sleeve 104 rotatably mounted in the outer knob shank. The end of 30 this sleeve is provided with a non-circular opening 105 which non-rotatably receives the complementary shaped end of the spindle portion 60. The slot 103 extends substantially 180° about the sleeve 104, thus giving ample room for the 35 required rotation of the inside knob to retract the latch bolt without rotation of the key barrel or the outside knob to which the key barrel is normally locked. With the parts shown in the 40 unlocked position in Fig. 1, either of the knobs may be rotated independently and, through the squared portion 57 on the spindle 55 or the squared portion 62 on the sleeve 61 as the case may be, will actuate one of the rollbacks to retract the latch.

It is desired, however, that the outside knob be dogged from the inside so that a person may not operate the latch bolt from the outside unless provided with the proper key. For this purpose a plunger or stem 70 is mounted in the inner 50 knob 48 for longitudinal movement, this member extending through the knob and having a manually engageable part 71 by which the user may actuate it. As shown in Figs. 1 and 8, the end of this member is disposed within the bore of the 55 knob shank 49 and adapted to engage the end of the spindle 55 so that it may move this spindle inwardly against the action of the spring 58 when the plunger is moved inwardly. In order to hold the spindle in its inward or dogging position 60 against the action of the spring 58, the plunger is provided with an L-shaped slot 72 (Fig. 8) in which is partially received a ball 73 contained in a hole in the knob shank 49. When the plunger 70 is moved inwardly, it may be rotated through 65 a slight turn until the ball lies in the transverse portion of the opening 72 which will prevent the return by the spring 58 of the plunger and spindle 55.

When the spindle 55 is thus moved inwardly by 70 the plunger from the position shown in Fig. 1 to the position shown in Fig. 2, it will be noted that the squared portion 57 still engages the rollback 27 so that this rollback may still be operated by the inner knob to retract the latch bolts.

However, it will be seen that the squared portion 62 on the sleeve 61 now lies within the squared opening 65 in the case 10 so that the sleeve 61 is prevented from rotation. As this sleeve is non-rotatably secured in the outer knob shank 42, the outer knob will be dogged against turning. In this position of the parts, the latch bolt may only be retracted from the outside by use of the proper key in the lock 47 as the spindle 55 will still be free to turn within the sleeve 61. The spindle may be restored to its original position by rotating the plunger 70 until the ball 73 lies within the longitudinal portion of the slot 72. The spring 58 will then move the spindle 55 outwardly.

It is also desirable in locks of this kind to provide guarding or dogging means to prevent the latch bolt being forced back by a tool inserted between the door and the door jamb. As shown more especially in Figs. 3 to 5, I have provided a dogging or guard lever 75 pivoted to the retractor stem 18 upon the pin 19, this lever being provided with a shoulder 76 adapted to engage the stop plate 22 within the lock case. At its forward end, this lever is provided with a laterally projecting nose 77 adapted to be engaged by the cross head 78 of a guard bolt 79 which projects from the lock case 10 at the trailing edge of the latch bolt 14 and which is provided with a stem 80 to which the cross head 78 is secured. The stem 80 projects through an opening in the member 17, and between this member and the guard bolt is disposed a spring 81 which tends to hold the guard bolt projected. The lever 75 is urged in a clockwise direction about its pivot 19 by the spring 82.

When the door is open the parts are in the position shown in Fig. 3 in which both latch bolt and guard bolt are protracted, and the cross head 78 by engagement with the nose 77 of the dogging lever 75 holds said nose 77 out of engagement with the head 20 of the bolt stem to permit the bolt to be cammed rearwardly into the case by engagement with the strike plate on the door jamb. Retraction of the latch bolt also retracts the guard bolt, but when the door reaches its final closed position and the latch bolt springs into the opening in the strike plate, the guard bolt will be held in its rearward position and the parts will be in the position shown in Fig. 4 where the nose 77 of the lever 75 lies behind the head 20.

If, in this position of the parts, pressure is exerted upon the end of the latch bolt tending to retract the same, the head 20 will strike the nose 77 and tend to move the lever 75 in a clockwise direction about its pivot 19, which movement, however, will be prevented by engagement of the shoulder 76 with the stop plate 22 so that the latch bolt will be dogged against retraction by pressure upon the end thereof. However, if, in this position of the parts, one of the knobs is turned to retract the latch bolt by means of the retractor 17, the lever 75, being pivoted on the retractor, will be moved rearwardly, and the engagement of the shoulder 76 with the stop plate 22 will move the lever 75 in a counter-clockwise direction against the action of its spring 82, and the shoulder 76 will be released from the stop plate 22, as shown in Fig. 5. In other words, when force is applied to the nose 77 of the lever 75 it tends to move it in a clockwise direction and engage the shoulder 76 with the stop plate 22, while if force is applied through the pin 19, when the retractor is moved rearwardly in the

case, the effect will be to move the lever 75 in a counter-clockwise direction and cause the shoulder 76 to disengage the stop plate 22 and thus permit retraction of the latch bolt.

In installing the lock, the aligning tube containing the outer knob mechanism is inserted through the opening 13 in the door. The latch bolt and retracting mechanism are contained in the case 10, and this case with its contained mechanism is inserted through the opening 10a in the edge of the door and through the opening 11 in the portion 12 of the aligning tube. When this has been done, the tube and case are secured rigidly together by the pin 83 which is inserted through openings in the portion 12 of the aligning tube provided therefor and through registering openings in the lock mechanism case 10. The inner knob mechanism carrying the inner rose 52 may now be inserted into the aligning tube together with the spindle 55 and the sleeve 61. After the retaining member 50 is put into place to hold the inside knob against removal, the sleeve 53 may be screwed up to hold the rose 52 against the door. If it is desired to mount the lock on a door of the other hand than that shown in the drawings, it is only necessary to rotate the case 10 about the shank of the outer knob before the inner knob is connected thereto, this rotation being possible by reason of the fact that slot 44 is annular and extends entirely around the knob shank 42. Thus the lock is universally applicable to doors of either hand and is also applicable to doors of regular or reverse bevel due to the provision of the identical square openings 65 and 65a at each side of the case 10 which are adapted to receive the squared portion 62 of the sleeve 61 so as to permit reversal of the lock case about its axis relatively to the cylindrical aligning tube.

While I have shown and described a preferred embodiment of my invention, it will be understood that it is not to be limited to the details shown, but is capable of modification and variation within the spirit of the invention and within the scope of the claims.

What I claim is:

1. A door lock comprising a case, a bolt and bolt-operating mechanism carried thereby, said mechanism including a retractor, said bolt being depressible relatively to the retractor, a dogging member pivotally mounted on the retractor and arranged to stand in the path of the bolt within the case when the door is in closed position to prevent retraction of the bolt by pressure on the outer end thereof, means fixed with respect to the case to engage said dogging member and prevent movement thereof in one direction about its pivot, and a guard bolt movably mounted in the case to engage and control the position of said member.

2. A door lock comprising a case, a bolt and bolt-operating mechanism carried thereby, said mechanism including a retractor, said bolt being depressible relatively to the retractor, a dogging member pivotally mounted to the retractor and arranged to stand in the path of the bolt within the case when the door is in closed position, means fixed with respect to the case to engage a part of said dogging member, said means engaging said dogging member on the same side of its pivot as the point of engagement of the bolt with the dogging member, whereby pressure by the bolt upon the dogging member causes said means to hold said dogging member against movement and thereby hold the bolt against retraction.

3. A door lock comprising a case, a bolt and bolt-operating mechanism carried thereby, said mechanism including a retractor, said bolt being depressible relatively to the retractor, a dogging member movably mounted on the retractor and arranged to stand in the path of the bolt within the case when the door is in closed position to prevent retraction of the bolt by pressure on the outer end thereof, and a guard bolt movably mounted in the case to engage and control the position of said dogging member.

4. A door lock comprising a case, a bolt and bolt-operating mechanism carried thereby, said mechanism including a retractor, said bolt being depressible relatively to the retractor, a dogging member movably mounted on the retractor and arranged to stand in the path of the bolt within the case when the door is in closed position to prevent retraction of the bolt by pressure on the outer end thereof, a guard bolt movably mounted in the case and having a part thereon to engage and move said dogging member to inoperative position when the guard bolt is in protracted position.

5. A door lock comprising a case, a bolt and bolt-operating mechanism carried thereby, said mechanism including a retractor, said bolt being depressible relatively to the retractor, a dogging lever pivoted to the retractor and having a nose portion standing in the path of the bolt within the case to prevent retraction of the latter by pressure on the outer end thereof, said dogging lever having a projecting shoulder thereon between the pivot point and said nose portion, and stop means in the case to engage said shoulder and hold the dogging lever against movement.

6. A door lock comprising a case, a bolt and bolt-operating mechanism carried thereby, said mechanism including a retractor, said bolt being depressible relatively to the retractor, a dogging lever pivoted to the retractor and having a nose portion standing in the path of the bolt within the case to prevent retraction of the latter by pressure on the outer end thereof, said dogging lever having a projecting shoulder thereon, stop means in the case to engage said shoulder and hold the dogging lever against movement, the pressure of the bolt on said nose portion of the dogging lever tending to move said lever about its pivot in a direction to engage said means, and a bolt reciprocably mounted in the case and hav-

ing a portion to engage the nose of said dogging lever and move the latter to inoperative position.

7. A door lock comprising a case, a bolt and bolt-operating mechanism carried thereby, said mechanism including a retractor, said bolt being depressible relatively to the retractor, a dogging lever pivoted to the retractor and having a nose portion standing in the path of the bolt within the case to prevent retraction of the latter by pressure on the outer end thereof, said dogging lever having a projecting shoulder thereon, stop means in the case to engage said shoulder and hold the dogging lever against movement, a spring normally urging said dogging lever to position to engage said bolt, and a spring-pressed guard bolt controlling the position of said dogging lever.

8. A door lock comprising a case, a bolt and bolt-operating mechanism carried thereby, said mechanism including a retractor, said bolt being depressible relatively to the retractor, a dogging lever pivoted to the retractor and having a nose portion standing in the path of the bolt within the case to prevent retraction of the latter by pressure on the outer end thereof, said dogging lever having a projecting shoulder thereon, stop means in the case to engage said shoulder and hold the dogging lever against movement, said shoulder being cammed out of engagement with said stop means when the retractor is moved rearwardly to retract the bolt, and a guard bolt reciprocably mounted in the case adjacent said first-named bolt and having a crosshead thereon and said crosshead being adapted to engage the nose portion of the dogging lever and move it to inoperative position when the guard bolt is protracted.
